(57) **CLAIM**

The ornamental design for an aircraft deep socket external drive tool, as shown and described.

DESCRIPTION

FIG. 1 is a perspective view of an aircraft deep socket external drive tool showing my new design;

FIG. 2 is a right-side elevational view thereof;

FIG. 3 is a left-side elevational view thereof;

FIG. 4 is a top plan view thereof, the bottom view being a mirror image thereof; and,

FIG. 5 is a front elevational view thereof, the rear being a mirror image thereof.
